[57] CLAIM

The ornamental design for a shoe outsole bottom, as
shown and described.

DESCRIPTION

FIG. 1 is a bottom plan view of a shoe outsole bottom
showing my new design;

FIG. 2 is a sectional view taken along line 2—2 of FIG.
1;

FIG. 3 is a sectional view taken along line 3—3 of FIG.
1;

FIG. 4 is a sectional view taken along line 4—4 of FIG.
1;

FIG. 5 is a lateral side elevational view of the shoe
outsole bottom of FIG. 1; and,

FIG. 6 is a medial side elevational view of the shoe
outsole bottom of FIG. 1.

The broken line showing of a shoe upper and sole periphery
is for illustrative purposes only and forms no
part of the claimed design.

FIG. 1

FIG. 2

FIG. 3

FIG. 4
